ADAPTER FOR ACCELERATORS FOR AUTOMOBILES

Filed Dec. 7, 1951

UNITED STATES PATENT OFFICE

2,688,262

ADAPTER FOR ACCELERATORS FOR AUTOMOBILES

William E. Bolton, New York, N. Y.

Application December 7, 1951, Serial No. 260,457

1 Claim. (Cl. 74—563)

1 This invention relates to accelerators for automobiles, and has for its object to provide a readily removable attachment to enable drivers of different stature to operate the accelerator in an energy saving manner.

The invention consists of an adapter for accelerators which may be readily attached or detached to an accelerator by which the bottom of the foot of the driver is raised to a level almost equal to the level of the brakepedal in order to minimize the ankle movement of the driver, and also to give the foot a good resting place during such ankle movement. This adapter consists of an elongated block of wood, plastic material or similar material having fastening clips at its under side to engage the accelerator plate, and having at its upper side or top, a friction material as rubber or the like to prevent the foot sole from slipping. Preferably, the inner or lower end of the adapter is provided with an inclined surface, to act as a rest for the heel of the driver.

The invention will be further described, an embodiment thereof shown in the drawings, and the invention will be finally pointed out in the claims.

In the accompanying drawings,

Fig. 1 is a perspective view of a clutch, brake pedal and accelerator placed, as known, on a dashboard floor, with, however, the improved adapter placed over the accelerator;

Fig. 2 is a vertical section taken on line 2—2 of Fig. 1;

Fig. 3 is a vertical section on line 3—3 of Fig. 1, and

Fig. 4 and Fig. 5 diagrammatical drawings, Fig. 4 showing the old relative heights of the brake pedal and accelerator, and Fig. 5 showing the new relationship of brake pedal and improved accelerator, taken on line 4—4 of Fig. 2.

Similar characters of reference indicate corresponding parts throughout the various views.

Referring to the drawings, the known floor 10 of a dashboard, has as known, the clutch pedal 11, the brake pedal 12 and the accelerator pedal 13. Normally, the distance of the surface of the brake pedal 12 from the surface of the known accelerator is shown by A in Fig. 4.

The average ankle movement of an individual is limited, depending partly on the size of an individual and partly on the mobility of the joint action of an individual. With a large throw of an ankle movement, there is a considerable strain to make the reach from the known accelerator to the brake pedal, and any strain invokes the leg muscles and often acts upon the knee. This soon becomes a fatigue producing action, whereas a

mere ankle movement is not so fatigue producing.

To assure a movement of the ankle within its limits, the accelerator 13 is provided with an adaptor 15, of a height to compensate for the excessive movement, and thus to reduce the distance between the upper surface of accelerator to the upper surface of the brake pedal to a factor B.

The known accelerator 13 is connected to a lever 16 which connects with the known mechanism which is not shown in detail, because known and which forms no part of the present invention. The metallic foot plate 17 usually has longitudinal beads 18 at its lower side, and is hinged at 19.

The improved adaptor 15 consists, preferably, of a block 20 of wood, or light metal. It can be made of glass, plastic, rubber or the like, or any other hard material. With slight adjustments this block 20 will fit on all American motor cars.

As a general indication of dimensions, without desiring to be limited thereto, this block 20 is 2 1/4" wide, 1 1/2" high, 7" long (bottom), 6" long (top), and 2" for the bevelled part 21. The rubber top coating 22 is 1/8". The metal clips 23 are 1/4" by 1/2". The overall length at the bottom is 7".

The metal plate 17 of the known accelerator usually has a rubber or the like layer 24 attached thereto to prevent slipping of the shoe of the driver.

The metal clips 23, may be applied in various ways. One way, as shown in Fig. 3, is to provide a strip 26 secured to the block 20 by screws 25, which strip 26 has a resilient bent end 27, at each end of the strip 26, so disposed that the bent ends 27 may be snapped over the sides of the plate 17 and its rubber like layer 24, and in consequence over each marginal bead 18. There are preferably four snaps 27, disposed two in front and two in the rear of the block 20; and this group of snaps 27 fasten the adaptor 15 to the accelerator plate 17.

The inclined part 21 of the block, also covered with rubber or the like, is made bevelled or inclined to provide for the heels, especially for high heels, so that the sole of the shoe can be placed flat on the layer 22.

The improved accelerator extension is designed for the comfort of the automobile driver. It contributes in a large degree to the safety of the public at large. Due to the fact that some people are short and others are tall it is impossible to build a car to fit every one. The improved accelerator extension remedies this situation. A short

person can reach the brake pedal but cannot reach the foot accelerator without stretching, this puts the body off balance and causes discomfort thus slowing the movement of the foot in the case of an emergency stop. Seconds lost in this operation could be the cause of serious personal injury and considerable amount of property damage. The improved accelerator extension brings the foot accelerator to a more even distance with the brake pedal providing more 10 comfortable driving and faster braking.

A tall person can reach the accelerator but when lifting the foot to apply the brake, his knee is likely to strike the steering wheel, this will prevent him from applying the brake and in turn may cause him to lose control of the car. The condition has caused many of our most serious accidents. The improved accelerator extension in this case will permit the driver to push the adjustable seat all the way back and allow ample 20 room for free and easy leg movement.

The improved accelerator extension is especially designed for high heels to afford firm footing and prevent possible slipping.

Should the occasion arise when more than one 25 person has the use of the car, the improved accelerator extension can be attached or removed in a few seconds.

I wish it to be understood that I do not desire to be limited to the exact details of construction 30 shown and described, for obvious modifications will occur to a person skilled in the art.

I claim:

In adaptors for accelerators for automobiles, having an accelerator pedal and a brake pedal closely adjacent to each other without any intervening structural element between the faces of 35 said accelerator and brake pedals at the levels of said faces of said pedals, the operative face of the accelerator pedal being disposed below the op-

erative face of said brake pedal as known, the combination of an elongated block of material of substantially the longitudinal length and width of said accelerator pedal operative face, and of a 5 thickness substantially equal to the difference in said levels of said accelerator and brake pedal operative faces, said block having a minor portion of its length inclined downwardly at its lower end extending downwardly from the upper surface of said block to said operative surface of said accelerator pedal, the lower end of said block being spaced from the lowest end of the pedal, said inclined portion facing the heel of the operator for resting the foot of the operator thereon, 15 means on the upper face of the block resisting any slipping action of the shoe applied thereto, and means for fastening said block to said accelerator pedal face, whereby the foot of the operator is substantially on the same level whether on the brake or block operative surface, it requiring only a right hand turning of the foot from the block to the brake pedal or vice versa without substantially elevating the foot to operate either the brake or the block operative 20 surface.
